TOY

Norman F. Rutherford, Central Islip, N. Y.

Application December 4, 1939, Serial No. 307,512

11 Claims. (Cl. 46—16)

The invention relates to toys and has as an object the provision of a toy which is a development of and improvement upon the toy known for years under the name of Jacob's ladder.

It is a further object of the invention to provide a toy which may assume many forms because of the embodiment therein of double acting hinges.

It is a further object of the invention to provide a Jacob's ladder type of toy comprising a plurality of blocks joined by double acting hinges, the end units of the thus formed series connected together also by double acting hinges to produce a closed system capable of many and astonishing movements.

It is a further object of the invention to provide a toy of the class described which may be provided with surfaces of different colors to render the manipulation thereof more attractive.

It is a still further object of the invention to provide a toy joined by double acting hinges, the hinge members displaying different colors upon the opposite sides thereof.

Further objects of the invention will appear from the following description when read in connection with the accompanying drawings showing illustrative embodiments of the invention, and wherein:

Figure 1 is a plan view of a pair of blocks connected with a double acting hinge;

Fig. 2 is an edge view of the structure of Figure 1;

Fig. 3 is a plan view of a second shape of block;

Fig. 4 is an edge view of the block of Figure 2 illustrating the action of the double acting hinge;

Fig. 5 is a central vertical section of the blocks of Figure 2 with the double acting hinge actuated in the opposite direction from that shown in Figure 4;

Fig. 6 is an edge view of a plurality of blocks connected with double acting hinges and brought to position for connection of the end elements of the series face to face to complete the toy of one form of the invention;

Fig. 7 is a side view seen from the right of the toy when in the position shown in Figure 6;

Fig. 8 is a plan view of a central block formed of two parts in accordance with one feature of the invention and with single uncompleted blocks shown at each side thereof;

Fig. 9 is an edge view of two of the pairs of blocks of Figs. 1 and 2 connected face to face;

Fig. 10 is a plan view of three blocks with

double acting hinges connecting the blocks at angles of 90°;

Fig. 11 is an edge view seen from the right of Figure 10;

Fig. 12 is a view similar to Figure 10 showing hexagonal blocks connected at 120° angles;

Fig. 13 is a combined view showing a variety of positions into which the completed toy of Figure 6 may be manipulated;

Fig. 14 is a view similar to Figure 9 illustrating a different method of constructing the blocks;

Fig. 15 is an edge view similar to Figure 2 showing hinges formed of double straps whereby to secure a varied color effect;

Fig. 16 is a perspective view of a pair of blocks connected with double acting hinges, the hinges differently colored on the two sides thereof;

Figs. 17 and 18 are plan views of the structure of Figure 16, opened in different positions;

Fig. 19 is a plan view of a form of the invention in process of manufacture in continuation of the stage of Figure 10 which when completed will comprise four blocks connected by double acting hinges at 90° angles;

Fig. 20 is an edge view of the form of Figure 19 completed;

Fig. 21 is a plan view of the structure of Figure 20 and Fig. 22 is a plan view of this form of the invention opened in one of its possible positions;

Fig. 23 is a form of toy in process of manufacture in further continuation of Figures 10 and 19 which comprises when completed six blocks connected into a closed system;

Fig. 24 is an edge view of the completed toy of Figure 23 in one of its possible positions of manipulation;

Fig. 25 is a plan view of a second possible position of the completed form of toy of Figure 23;

Fig. 26 is a view similar to Figure 23 showing a toy comprising when completed eight blocks connected at 90° angles with each other by means of double acting hinges;

Figs. 27, 28, 29, and 30 are views of possible positions of manipulation of the completed toy of Figure 26;

Figs. 31 and 32 show in plan view completed toys comprising hexagonal blocks connected by double acting hinges alternately at 90° and 120° angles showing color schemes upon opposite sides thereof;

Figs. 33 and 34 are different positions into which the toy of Figures 31 and 32 may be manipulated;

Fig. 35 is a plan view of a toy in process of manufacture;

Fig. 36 is an edge view of the toy of Figure 35 folded for connection of one of the half blocks at one end of the chain to the remaining half block at the opposite end of the chain;

Fig. 37 is a plan view of one position into which the toy of Figure 36 may be manipulated; and

Fig. 38 is a plan view showing blocks in the form of polygons with an odd number of sides.

In the Jacob's ladder above referred to a series of blocks are each connected to an adjacent block at each side thereof, the blocks being in alignment in chain formation. The present invention is the result of experimenting with different forms of this toy having the end blocks of the chain connected to form a closed system.

As shown in Figures 1, 2, 4, and 5, single blocks 40, 41 are shown having one hinge comprising the two straps 42 connected as at 43, 20 44 to the lower side of the block 40 and the remaining ends of the straps 42 connected as at 45, 46 to the lower surface of the block 41. The single strap 47 comprising the remaining portion of the double acting hinge is shown as connected at 48 to the lower side of the block 41 and at 49 to the lower side of the block 40.

It will be seen that all the connections 43, 44, 45, 46, and 48, 49 are thus brought upon the lower surface of the two blocks as seen in Figure 1. By this expedient the toy of say Figure 6, may be made up of elements such as shown in Figures 1, 2, 4, and 5 by superposition of two of the blocks as 40, 41 into the position shown in Figure 8 and 9 with the end fastening of the hinges concealed between the blocks.

In Figure 9 I have designated the superposed blocks as 40 and 41, one element corresponding to Figure 2 being inverted and reversed in its position in Figure 9. The positions of other pairs of blocks 40, 41 are shown in dotted lines in Figure 9 in position to form the chain of Figure 6.

When the chain of blocks is completed after the manner described above and illustrated in Figure 9, and including the desired number of blocks as say seven complete blocks and two half-blocks, the chain may be brought to the position shown in Figure 6 or its equivalent and the end half-blocks of the chain may be secured face to face to complete a closed system. The system ready for its final closure in the position shown in Figure 6 is shown in side elevation in Figure 7 to illustrate the position of the ends of the straps of the hinges where they pass about the ends of the blocks 40, 41.

When the blocks are in different positions the straps will fall sometimes with one side of the strap exposed and at other times with the other side of the same strap exposed. Thus, if the completed system of Figure 6 be opened into a hollow square as shown at 50, Figure 13, all the inside exposed hinges may be caused to display a single color and the outside exposed hinges another color. If desired, the exposed portions of the blocks themselves may be colored to match the exposed portions of the hinges in the position 50.

The open square formation 50, may be turned inside out to reverse the color aspect of the two sides, a result which appears impossible upon casual inspection. This may be accomplished by virtue of the double acting hinges whereby it is possible to successively turn the blocks "end for end."

In addition to this possible manipulation of the toy of Figure 13, the blocks may be brought into the different forms in said figure, among others, thus producing a novel and interesting toy or puzzle.

For the purpose of causing the straps of the hinges to display different colors on their opposite sides, the opposite sides of a single thickness of strap may be vari-colored. As an alternative, two straps of different colors may be superposed and utilized as a single strap in the manner illustrated in Figure 15, wherein the strap 52 may be one color and the strap 53 a second color. Likewise the straps 54 and 55 may be of other colors differing from each other and from that of straps 52, 53.

The spaces 56, 57 and 58 upon one side of the block exposed in the position of Figure 15 may also be given different colors and different from the straps, if desired, and the corresponding spaces 59, 60 and 61 may be colored differently from each other and from any of the straps to further modify the color effect when the blocks are opened in different directions about the double acting hinges.

For some purposes it is desirable to form the faces of the blocks of thin material as Celluloid, in which event the blocks of the units, as shown in Figures 1 and 2, 9 or 15 would be so thin that when superposed in the position of Figure 9, the result would be too thin to be effective. In such case the structure of Figure 14 may be adopted wherein the core 62 is shown placed between the blocks when they are assembled in the manner of Figure 9.

As a further development of the invention square blocks as shown in Figure 10 may be formed which are similar to the blocks of Figure 1 but the assembly of Figure 9 is carried out in such a manner that each successive block of the chain is joined to the next block at right angles. In this manner a chain such as shown in Figure 19 comprising blocks 40, 41 may be constructed, said chain made up of three complete blocks when assembled and the two half-blocks 40, 41 projecting from the end of the chain. This chain may be then folded into the position of Figure 20 when the exposed surface of block 41, seen at the right of Figure 19, will come face to face with the under surface of the block 40. These blocks may then be secured together to produce the completed toy of Figures 20-22 inclusive.

An edge view of this structure is shown in Figure 20 and the side view in Figure 21, lined to show different colors. This toy may be opened from the position of Figure 21 to the position of Figure 22 about the hinges at either side of the form of Figure 21, and from the position of Figure 22 may be folded back to the position of Figure 21 with a second face of units exposed on the two sides of the Figure 21 position. The toy may then be opened about another edge and by manipulation the upper surface of the toy in the position of Figure 22 may be caused to display four aspects vari-colored as desired.

A further form of the toy of the nature of Figures 19-22 inclusive may be formed in the manner shown in Figure 23, the chain comprising five complete blocks and two half-blocks. This may be then folded to the position of Figure 24 when the two half-blocks will be superposed to bring the faces of the two half-blocks 40 at the ends of the chain into registry whereupon they may be fastened together.

This form of toy may be manipulated by opening at the points 63, the blocks swinging to the position shown in Figure 25, which movement may be continued until the position of Figure 24 is again reached but with a different aspect of the blocks exposed on the exterior.

In this way therefore the form of Figure 24 may be caused to display four different color effects in the angles thereof, wherein the faces of the blocks are exposed.

In the form of Figure 26 the blocks are assembled in the same manner as shown in Figure 19 except that seven complete blocks and two half-blocks are utilized to produce the chain. This form is then folded to the position of Figure 27 whereupon the end half-blocks 40, 41 will be brought face to face and may be secured together to constitute the closed system. This form may be folded in the position of Figure 27 or Figure 28.

When in the position of Figure 28, the blocks may be manipulated by opening at the points 64 to the position of Figure 30 after the manner of Figures 24 and 25. They may be also opened into the position of Figure 29 with four blocks exposed, from which position the blocks upon one side may be folded in opposite directions to bring them to the position of Figure 27 from which position they may be opened again to the position of Figure 29 with different surfaces exposed and by different manipulations may be caused to display a plurality of different aspects.

In another form of the invention the toy is constructed of polygonal blocks. One form of unit for such blocks is shown in Figure 3 comprising at 65, 66, hexagonal blocks connected to each other by double acting hinges with the ends secured to the blocks at the lower surface thereof. The toys, to be formed of the units of Figure 3 in the same general manner as indicated in Figure 9 for rectangular blocks, will comprise two of the half blocks 65, 66.

The successive blocks of a chain made up of the unit of Figure 3 may be connected in the manner shown in Figure 12 wherein a block 65 is shown superposed on a block 66 with two half blocks 65, 66 projecting from the thus completed unit at an angle of 120° to each other. In this manner a chain may be completed to comprise five completed blocks and their half blocks, which half blocks may be united to each other to complete the closed system of Figure 31.

This system may be brought to the position of Figure 34 by lifting from the plane the points 67, 68, 69 with a movement forwardly of the adjacent blocks about the hinge joints 70, 71, and 72, to assume the position of Figure 34. A continuance of this movement will bring the toy into the position of Figure 33 from which position by opening the pairs of blocks 73, 74 and 75 from the opposite side, the position of Figure 34 may be secured, which upon continuance will bring the blocks to the position of Figure 32 with another aspect of the blocks exposed.

In the manner above described hexagonal chains may be shown having four different aspects exposed which may be vari-colored in accordance with the principles already explained.

Instead of connecting the half blocks continuously in the manner shown in Figure 12, they may be connected in the manner of Figure 35 showing five completed blocks and half blocks 65, 66 at each end thereof. It will be seen that in this chain the 120° angles are reversed whereas in the form of Figure 12 the 120° angles de-

part in the same direction at all times from the preceding block.

The chain of Figure 35 may be folded to the position of Figure 36 whereupon the half block 5 65 is brought face to face with the remaining half block 66 which are then secured together.

This form of the invention may be manipulated in the manner shown in Figure 37 by opening with two blocks in the location 76, 77 and 10 one block at 78, 79, from which position they will again swing to the position of Figure 36, but at each movement a different external aspect will appear running through six changes of color. It is obvious that other forms may be produced by using polygons of different numbers of sides connecting the successive blocks of the polygons with double acting hinges at different arrangements of angles and by producing the forms herein shown by varying numbers of 15 blocks in the closed system.

Fundamentally the invention depends upon chains of blocks connected by double acting hinges into a closed system by first producing a chain of such blocks and then by connecting the ends.

The manner of connection of polygons having an uneven number of sides is shown in Figure 38 where pentagons are utilized.

An important feature of the invention in addition to that just mentioned is the provision of a display of varying colors by coloring straps differently upon the two sides or by using two part straps. The cross hatching throughout the drawings with the single exception of Figure 5 35 represents color.

The effect of the double acting hinges upon such a closed system and the manipulations possible with the results are difficult to clearly state on paper. However the above description disclosing the manner of construction of the toy will enable those skilled in the art to produce and discover the manipulation of the completed toys by experiments.

Minor changes may be made in the physical 45 embodiments of the invention within the scope of the appended claims without departing from the spirit thereof.

I claim:

1. A toy comprising, in combination: a plurality of blocks connected in series by double acting hinges; the end blocks of the series connected with each other also by double acting hinges to provide a closed system.

2. A toy comprising, a combination: a plurality of blocks connected in series by double acting hinges; the end blocks of the series connected to each other also by double acting hinges to provide a closed system; certain of the hinges which connect certain of the blocks of the system to one of their adjacent blocks forming an angle other than 180° to the hinges connecting said certain blocks to their other adjacent blocks.

3. A toy formed of a plurality of pairs of single blocks, the blocks of each pair united by double acting strap hinges; alternate of said pairs inverted relative to adjacent pairs and a block of each pair in a series connected face to face with a relatively reversed block of an adjacent pair to provide a chain of compound blocks connected by double acting hinges.

4. A toy comprising, in combination: a chain of the compound blocks of claim 3 with the end single blocks of the chain united face to face in like manner as the said body of the chain to provide a closed system.

5. The combination of claim 3 wherein the straps composing the hinges differ in appearance upon opposite sides.
6. The combination of claim 3 wherein the straps composing the hinges are composed of a double thickness of straps of different appearance.
7. The combination of claim 4 in which the single blocks are polygons with sides of uniform length and in which the resulting chain is produced by connecting reversed pairs of single blocks with the polygons in registry but with the hinges out of alignment.
8. The combination of claim 3 in which the ends of the straps composing the hinges are secured to the faces of the single blocks which are opposed by and connected to the reversed faces of the adjacent pairs of single blocks where-

by to be concealed between the connected faces.

9. A toy comprising, in combination: a plurality of rectangular blocks each connected at opposite edges to adjacent like blocks by double acting hinges to form a closed system.

10. A toy comprising, in combination: a multiple of four rectangular blocks each block connected at opposite edges to adjacent like blocks by double acting hinges to form a closed system.

11. A toy comprising, in combination: a multiple of four rectangular blocks each connected at opposite edges to adjacent blocks by double acting strap hinges to form a closed system; opposite sides of the straps forming said hinges differing in appearance.

NORMAN F. RUTHERFORD.
